MULTIPLE ARCH DAM

Application filed August 8, 1927. Serial No. 211,837.

My invention relates to structures for damming streams and rivers and is particularly related to a novel form of dam comprising a plurality of arches.

An object of my invention is to provide a dam which requires but a small amount of material.

Another object of my invention is to provide a dam in which the stresses are transmitted to the foundation in an efficient manner.

My invention possesses other advantageous features, some of which with the foregoing will be set forth at length in the following description where I shall outline in full that form of the multiple arch dam of my invention, which I have selected for illustration in the drawings accompanying and forming part of the present specification. In said drawings I have shown one form of multiple arch dam embodying my invention, but it is to be understood that I do not limit myself to such form since the invention, as set forth in the claims, may be embodied in a plurality of forms.

In the drawings:

Fig. 1 is a plan of one form of dam of my invention.

Fig. 2 is a cross section of the dam shown in Fig. 1, the plane of section being indicated by line 2—2.

Fig. 3 is a plan of a modified form of dam of my invention.

Fig. 4 is a cross-section on the line 4—4 of Fig. 3.

Fig. 5 is a plan of another modified form of my dam.

Fig. 6 is a cross section on the line 6—6 of Fig. 5.

Fig. 7 is a horizontal section on the line 7—7 of Fig. 8 of a variant form of dam of my invention.

Fig. 8 is a cross section of the dam disclosed in Fig. 7, the plane of section being indicated by line 8—8 of Fig. 7.

In its preferred form, the dam of my invention preferably comprises a plurality of conoidal shells or arches arranged in juxtaposition with their axes substantially intersecting.

There are various ways of building a dam according to my invention, and I disclose some of these various ways herein. In each instance, the dam comprises a plurality of arches or shells, each of which is a portion of a cone. The cone on which the arch is constructed can be either circular or ellipsoidal and any portion of a conical surface can be utilized. As shown in Fig. 1, the dam comprises a central conical arch or shell 6 extending substantially across the walls 7 and 8 of the canyon in which the dam is situated. At either side of the central shell 6, are side shells 9 and 11 also of conoidal contour and preferably arranged with the cone elements 65 parallel to the cone elements of the central shell 6 at the springing lines of the arches. In this manner the axes of the conoidal surfaces converge. The shells 6, 9, and 11 are supported by buttresses 12 and 13, which 60 originate at the springing lines of the arches and extend in diverging planes to the walls 7 and 8 of the canyon. 70

By virtue of this construction I am enabled to save considerable material in constructing 75 the buttresses as their bases extend up the walls of the canyon. Advantage is taken of the slope of the canyon walls 7 and 8 so that the terminations of the heel portions of the buttresses are considerably above the toe portions. Not only is there a firm support 80 provided for the dam by the canyon walls but a large amount of material and labor is saved in constructing the buttresses. A further advantage of the conoidal shell construction is 85 that the radius of the arch surface decreases uniformly from the top toward the bottom of the arch. Since the thickness of the arch at any point is determined by the hydraulic pressure and the arch radius at that point 90 the decreasing radius toward the bottom of the shell counteracts in a measure the increasing hydraulic pressure with the depth and consequently permits a relatively thin arch section to be used.

In Fig. 3 is disclosed a somewhat modified form of dam in which the dam extends somewhat straighter across the canyon walls 16 and 17 than the dam shown in Fig. 1. In this instance, the decrease in radius of the 100

conoidal surface toward the bottom of the dam is taken advantage of to lessen the necessary dimensions of the arch ring. In addition, the various conoidal shells 18, 19 and 20 comprising the dam are arranged in such relationship that the angle subtended by any particular horizontal section or any section normal to the axis of the central arch varies with the height of the arch. The angles subtended by the conoidal surface exposed in the central arch 19 at various elevations taken along the conoidal axis are indicated on the figure. It will be seen that the subtended angles decrease considerably toward the top of the arch. This decrease is not a constant amount but varies with the height. Adjacent the contact of the arch 19 with the ground in the canyon, the subtended angles vary but little, while as the arch leaves the ground and extends upwardly, the subtended angles at successive elevations become less. Inasmuch as the subtended angle included within the sides of each shell is increased as the bottom of the shell is approached, considerable material can be saved in the construction of the shells inasmuch as the maximum fiber stresses in the material decrease with an increased subtended angle of the arch. An additional economy is thereby effected. At the springing lines of the arches 18, 19 and 20, buttresses 21 and 22 are provided for supporting the shells and the buttresses diverge considerably from parallel position so that a large amount of material is saved in their construction and so that they provide a firm support for the dam.

A somewhat similar form of dam is disclosed in Figs. 5 and 6 in which the conoidal shells 23, 24 and 25 are arranged with their elements non-parallel at the springing lines and are supported by diverging buttresses 27 and 28. In this instance the angles subtended by the springing lines of the central shell 24 vary considerably between the lowermost portion and the top of the shell. Arch rings taken at equal intervals thruout the height of the shell and either in horizontal planes or in planes normal to the axis of the conoidal surface disclose that the subtended angles increase somewhat until the central shell intersects the forward faces 29 and 31 of the buttresses 27 and 28, thence remaining substantially constant until the surfaces of the shells 23, 24 and 25 intersect. These intersecting surfaces are mathematically parabolas but in practice are so nearly straight lines that they can be considered as such herein. The intersecting surfaces cause the angles subtended by the upper portions of the arch 24 to decrease at a constant rate until they are approximately of the same value at the top as they are at the very bottom.

The form of dam disclosed in Figs. 7 and 8 is fundamentally the same inasmuch as it includes a central arch 32 and flanking arches

33 and 34, all of which are conoidal surfaces arranged in order across a canyon. The conoidal shells are supported by buttresses 36 and 37 diverging in the usual manner but the feature of this modification is that the forward faces of the buttresses 36 and 37 are in themselves supplementary conoidal shells 38 and 39 which intersect the shells 32, 33 and 34. Inasmuch as the pressure is distributed by the supplemental arches 38 and 39, the interior of the buttresses 36 and 37 can be made hollow and a saving in material is thereby effected.

In all forms of the dam of my invention, the arches or shell sections are conoidal in form and are arranged so that the supporting buttresses diverge. This construction permits the use of considerably less material in forming the arches and in forming the buttresses and provides at a less cost a dam equal in strength and stability to those in use.

I claim:

1. A multiple arch dam comprising a plurality of conoidal shells arranged in juxtaposition with their apices toward the base of the dam, and supplementary conoidal shells in abutment with said first named shells and having their apices toward the top of the dam.

2. A multiple arch dam comprising a plurality of conoidal shells in juxtaposition, alternate shells being inverted.

3. A multiple arch dam comprising a plurality of alternately upright and inverted conoidal shells in juxtaposition.

4. A multiple arch dam comprising a plurality of substantially upright and inverted conoidal shells in juxtaposition.

In testimony whereof, I have hereunto set my hand.

RUDOLPH W. VAN NORDEN.
